UNITED STATES PATENT OFFICE.

JAMES MORAN, OF NEW YORK, N. Y.

FLUID-FUEL BURNER.

SPECIFICATION forming part of Letters Patent No. 712,835, dated November 4, 1902.

Application filed February 10, 1902. Serial No. 93,409. (No model.)

To all whom it may concern:

Be it known that I, JAMES MORAN, of the city, county, and State of New York, have invented certain new and useful Improvements 5 in Fluid-Fuel Burners, of which the following is a full, clear, and exact specification, reference being had to the accompanying drawings, wherein—

Figure 1 is a horizontal sectional view of a 10 pressure-pipe and burner embodying my invention; Fig. 2, a cross-sectional view thereof on lines 2 2 indicated in Fig. 1; Fig. 3, a similar view like Fig. 2, showing a modified construction embodying my invention; Fig. 4, an 15 enlarged detail cross-sectional view of the burner-bushing and valve-seat and of the burner detached therefrom; and Fig. 5, an enlarged detail view, an elevation of the 20 valve-plug and valve-stem, also separated from each other.

My invention relates to devices for utilization of fluid fuels, and more particularly to burners for crude liquid fuel, though my improvement is equally well applicable to any 25 liquid-fuel burner where the oil is forcibly driven through a nozzle into a carburetor, gas-generator, or into an oven or furnace.

The drawings illustrate a carburizing or 30 hydrocarbon burner embodying my invention.

Referring to Fig. 1, A is what is designated in the art as the "pressure-pipe." b is a web dividing the interior of the pipe into two compartments A' and A². The compartment A' 35 is connected to a steam-generator or compressed-air reservoir. Compartment A² is connected to the oil-pump or oil-reservoir, from which the oil is driven under pressure. B is a nozzle screwed in flange c of the 40 pressure-pipe and communicating with the compartment A'. C is a nozzle communicating with the compartment A². This is the ordinary arrangement of a hydrocarbon or carburizing burner, and I do not claim this arrangement as any part of my invention.

My invention consists in the particular arrangement of the connection of the nozzle C with the web b by means of the bushing and valve-seat d, and in the combination there- 45 with of the valve D, having a separable plug G affixed thereto, as will be explained more fully hereinafter.

The proper operation and function of any oil-burner requires, however, the oil to be driven forcibly through the nozzle and that 55 the volume of its flow be capable of regulating, diminishing, or increasing without reducing or increasing the force of the pressure upon the oil.

All oil used as liquid fuel is generally crude 60 oil containing considerable quantities of corroding impurities and sand, which affect injuriously the valves through which the oil is so forcibly driven, thus necessitating the very frequent regrinding and replacing of the 65 valve parts. For this reason burners wherein the flow of the oil is regulated by diminishing or increasing the pressure upon the oil are prevalently used, though they are not as efficient. It is also necessary to make the 70 cross-sectional area of the burner-tube exactly as required for the flame, and then the requisite pressure must practically be made constant. Such burners are quickly worn out, sand and other impurities grinding the 75 interior of the burner-tube and enlarging its orifice, thereby reducing the discharging velocity of the oil, which in turn again affects detrimentally the carburizing or other process.

The use of needle-valves for regulating of 80 the volume of the flow of the oil through the burner-tube was found impracticable owing to the corroding and grinding effects of the oil, which rapidly ruined the valve and the valve-seat. Considering this circumstance 85 and the defects of such arrangements wherein such valves for regulating the flow of the oil are not used I devised the burner shown in the drawings and hereinafter described with the object in view to enable the flow of 90 the fluid fuel to be regulated by means of such a valve and to obviate the difficulties heretofore encountered. For this purpose I provide a flanged aperture a in the web b of the pressure-tube. This aperture is screw- 95 threaded, and into it I fit the bushing d, having one end of its bore preferably beveled and ground to form a seat i for the valve- plug g. The other end of the bore of the bushing d is recessed and provided with an 100 internal screw-thread. Into this screw-threaded recess a' the socket j of the burner-tube or nozzle C is fitted and tightly screwed therein. The bushing d is made, preferably, of some

hard metallic composition; but it may also be made of some metal or other substance which permits its being hardened after finishing the bushing. The object of using this bushing is twofold—first, to enable me to produce a valve-seat which will withstand the deteriorating action of the fuel ingredients passing through it, and, second, to reduce the cost of repairs, in that only this bushing needs to be replaced when its orifice is so worn out as to render it ineffective for closing the nozzle by means of the valve-plug *g*. The use of the bushing also aids in preserving the nozzle, and the interposition of the bushing between the nozzle and the pressure-tube tends to preserve the solidity of the connection between the fuel-conductor and the nozzle. Opposite the aperture in the web *b*, wherein bushing *d* is screwed, another aperture *h* is provided in the pressure-tube. This aperture is located concentrically with the other, and into it is screwed valve-box *F*.

The screw-threaded stem *f* of valve *D*, having a slot or bore *n* on its end and a hand-wheel or knob *o* on the other end, is filled into the aperture *l* of valve-box *F*, screw-threaded in the bottom of the box and smooth in the top. A suitable packing *q* is inserted in the recess in the top of the valve-box, held therein by hollow plug *r*, screwed on top of it. The slot or aperture *n* in the end of stem *f* serves to receive the stem of valve-plug *g*, secured to the stem by cross-pin *p*, inserted through a bore extending through the stem and the stem *m* of the valve-plug. This arrangement is provided to enable the replacing of valve-plug *g* when worn out and preserving the valve-stem. The arrangement of this connection is shown in the detail Fig. 5. In this figure the stem of the plug *g* is shown to be screw-threaded. Such arrangement makes the connection more rigid, but is not essential for the operations of my device.

Plug *g* is made, preferably, of hard metallic composition or other material permitting the hardening thereof after finishing. The point of this valve-plug *g* is fitted into the valve-seat *i*, provided in the bushing.

The operation of the device is plain from the description of its construction. The fuel may be driven under any desired pressure. The volume of its flow is minutely regulated by setting the valve *D* accordingly. By means of this valve also the flow of the fuel is stopped. As stated above, such fluid fuel contains a large quantity of impurities, and of these the heavier ones—more particularly the sand—settle in the bottom of the pressure-pipe during the periods the burner is not used. On restarting the burner the motion of the oil raises these heavier impurities and drives them into the fuel tube or nozzle *C*,

thereby often clogging it and closing the flow of the fuel. To avoid this, I provide in the bottom of the pressure-pipe, underneath the bushing *d*, a flanged aperture *t*, in which an outlet-pipe *u* is secured and provided with a stop-cock *w*. In this recess the heavier impurities settle when the flow of the fuel is stopped, and then if before opening the valve *D* and starting the burner the cock *w* is turned the sediment of these impurities is discharged and the clogging of nozzle *C* avoided.

In Fig. 3 a somewhat-modified construction of my improvement is shown. In this structure the valve-box is omitted and the screw-threaded aperture for the stem of the valve *D* is provided in a boss cast upon the pressure-pipe. A part of the aperture *l* on the outside of the pressure-tube is enlarged, and in the recess formed thereby packing *q'* is set and held in its place by plug *r'*. Furthermore, the bushing *d'* is set reversely in the web *b'*, being screwed in through the aperture in the pressure-pipe wherein the nozzle *B'* is secured. In this construction nozzle *C'* and bushing *d'* can only be removed from that side and through the aperture where the nozzle *B'* is screwed to the pressure-pipe. In the construction previously described, and shown in Figs. 1 and 2, the nozzle *C* and bushing *d* can be removed through either side after valve-box *F* or nozzle *B* are unscrewed. This arrangement possesses the advantage that the burner may be repaired or any part thereof exchanged without removing the pressure-tube from its position in the apparatus where the burner is used.

I claim as my invention—

A fluid-fuel burner comprising a pressure-tube, divided by a web having a flanged, screw-threaded aperture, approximately in the center thereof; a screw-threaded bushing, having one end of its bore shaped to form a valve-seat, and the other end of its bore recessed and provided with an internal screw-thread; a nozzle screwed in the recess of the bushing; screw-threaded apertures in the walls of the pressure-tube, concentrically located with the aperture of the web; a valve-stem screwed in the aperture of the wall of the pressure-tube, opposite the valve-seat of the bushing; a valve-plug, fitted into the valve-seat, removably secured to the valve-stem, and an outer nozzle screwed in the aperture in the wall of the pressure-tube, concentrical with and surrounding the nozzle screwed in the recess of the bushing, substantially as herein shown and described.

JAMES MORAN.
